R. S. O'NEIL,
ELECTRICAL INDICATING DEVICE,
APPLICATION FILED MAR 1, 1920.

1,374,948.

Patented Apr. 19, 1921.

UNITED STATES PATENT OFFICE.

RODOLPH STUART O'NEIL, OF LONDON, ENGLAND.

ELECTRICAL INDICATING DEVICE.

1,374,948.

Specification of Letters Patent. Patented Apr. 19, 1921.

Application filed March 1, 1920. Serial No. 362,418.

To all whom it may concern:

Be it known that I, RODOLPH STUART O'NEIL, a subject of the King of Great Britain, and a resident of London, England, have invented certain new and useful Improvements in Electrical Indicating Devices, of which the following is a specification.

This invention relates to electrical indicating devices, and has particular reference to indicators for use in apparatus for signaling the position of a ship's helm. Although regarded as useful in other signaling systems it is particularly advantageous in systems such as that disclosed in the specification of my application.

The invention consists of an indicator comprising a casing having a single display opening, a single illuminating device behind said opening, magnetically operated color screens adapted to be pre-selected for interposition between the illuminating device and the display opening, and electro-magnetically operated indicating disks adapted to be pre-selected and interposed between the color screen in operative position and the display opening whereby a pre-selected indication in a pre-selected color is displayed.

The invention is illustrated diagrammatically in the accompanying drawing which is a sectional diagram.

The invention bears some resemblance to that described in my application for Letters Patent of the United States, filed Mar. 1, 1920, Serial number 362,418, in that electro-magnetically operated disks are employed and are in operation interposed between an illuminating device and a display opening, but it differs from it in that instead of employing separate lamps to give various color indications I propose to employ a single white light and obtain the desired color effects by interposing pre-selected color screens by electro-magnetic operation.

This will be understood upon reference to the drawing wherein the numeral 1 designates the illuminating device or lamp and 2

and 3 designate color screens. In a helm 50 signaling indicator one of the screens will be green and the other red. The screens are brought into operative position by the electro-magnets 4 and 5 respectively. That is to say, when the magnet 4 is in circuit the 55 screen 2 is moved into display position and when the magnet 5 is in circuit the screen 3 is moved into display position. A further series of magnetically operated disks 6 are provided arranged annularly around the 60 display opening 7 and these disks have applied to them the figures or other indications it is desired to display. They are operated by the magnets 8 which when energized attract armatures 9 and through the 65 links 10 move the disk into operative display position. The arrangement is precisely similar to that described in my companion application of even date and the 70 operation is also similar except that as before described whenever the helm is on either side of the central position the light 1 is illuminated and one or other of the 75 color screens 2 and 3—according to whether the rudder has moved to "port" or "starboard"—is interposed between the lamp 1 and the display opening 7.

Although I have described my invention in its application to helm signaling, it will be understood that it may be applied to 80 other indicators.

What I claim and desire to secure by Letters Patent.

An electrical indicator comprising a casing having a single display opening, a single illuminating device behind said opening, magnetically operated color screens adapted to be pre-selected for interposition between the illuminating device and the display opening, and electro-magnetically operated indicating disks having indicia and adapted to be pre-selected and interposed between the color screen in operative position and the display opening whereby a pre-selected indication in a pre-selected color is 95 displayed, substantially as specified.

In witness whereof I affix my signature.
RODOLPH STUART O'NEIL.
